UNITED STATES PATENT OFFICE.

RAYMOND M. ANDERSON, OF DETROIT, MICHIGAN, ASSIGNOR TO GEORGE M. HOLLEY,
OF DETROIT, MICHIGAN.

CARBURETER.

1,390,477.

Specification of Letters Patent. Patented Sept. 13, 1921.

Application filed April 8, 1920. Serial No. 372,323.

To all whom it may concern:

Be it known that I, RAYMOND M. ANDERSON, citizen of the United States, residing at Detroit, in the county of Wayne and State 5 of Michigan, have invented certain new and useful Improvements in Carbureters, of which the following is a specification.

This invention relates to improvements in carbureters of the type in which an air 10 vented fuel well supplies all the fuel required for both, low speed and high speed 15 operation.

Figure I shows diagrammatically the cross 20 sectional elevation of the carbureter. Fig. II shows a transverse vertical section taken 25 at right angles to the plane in which Fig. I is taken.

The particular defect in carbureters of 30 this type heretofore built has been that when 35 transferring from the low speed nozzle to the main nozzle, there has been within the air-vented fuel well, a sudden reversal of flow which reversal is the cause of irregular 40 running and missing, especially noticeable 45 when the engine is cold. To obviate this serious defect, the parts are so arranged that no reversal ever takes place, the low speed fuel being led out of the air-vented well at 50 a point adjacent to the point at which the fuel for high speed is delivered into the main air passage.

Description.

The application of this principle to a plain 55 tube carbureter is shown on the drawing in which A is the air entrance, B a restriction of venturi form, C is the mixture outlet controlled by a throttle D. E is one auxiliary air passage, F is another. G and H are the 60 outlets from the passage E leading respectively to the Venturi tube B and to that portion of the mixture outlet C adjacent to the throttle valve, D. J is the outlet or nozzle from the passage F into the Venturi tube 65 B and K is the constant level fuel reservoir feeding fuel into chamber L, connecting passage F and outlet J through the regulable fuel outlet M, controlled by a needle valve N. O is an adjustable means for regulating 70 and atomizing the low speed fuel delivered adjacent to the lip of the throttle D and is provided with an eccentric cavity P and a communicating passage Q of suitable size. To facilitate starting a small "bleeder" R 75 may be provided between the outlet or nozzle 80 and the chamber L or the outlet G may be below the level of the fuel in K so that when the engine is not running, the passages E, G and H may fill up with fuel. An auxiliary throttle S may be provided in air entrance A. The operation of the carbureter 85 is as follows:

On starting the engine the throttle is opened about one-fifth and the starting choke (S) closed four-fifths of the way. The 90 engine is then cranked and the fuel lying in the passages (E), (G), and (H) is violently ejected at (P) and there atomized by reason of the eddy at the tip of the throttle. The fuel lying in the passages (J) and (F) also commences to move by reason of the sub-atmospheric pressure within the 95 vacuum chamber.

After the engine is run for a short period of time with the starting choke (S) partially closed, the engine is sufficiently 100 warmed for the starting choke to be opened and normal idling ensues.

Considering the normal idling as distinct from starting, we have, in the Venturi tube 105 when running under throttle, an extremely slight vacuum due to the air flowing to the partially opened throttle (D). This vacuum, which is sufficient to raise fuel up the nozzle (J), would, if no other provision were 110 made or arranged, cause the fuel to leak over the outside of the nozzle and run down to be wasted. By the provision of the tube (G) this fuel flows through (G) to the low speed tube (H). In addition to the fuel 115 flowing down (G), fuel is picked up at (R), but the sizes of the various passages are so arranged that the fuel drawn through (R) does not cause a material drop of the 120 level in the nozzle (J), so that the fuel is 125 always maintained at or near the tip of the nozzle (G). The fuel in the annular nozzle (J) is thus in actual movement, and its 130 inertia is thus less detrimental than it otherwise would be when a sudden demand is 135 made upon the fuel in (J), which demand occurs when the throttle is suddenly opened, the fuel in (F) supplying the demand.

I claim:

1. In a carbureter, a main air passage, a 140 throttle valve, a main fuel nozzle delivering into said main air passage on the atmospheric side of said throttle, a constant level reservoir having a regulable outlet, a passage connecting said reservoir outlet and said 145

fuel nozzle, a low speed fuel outlet slightly in advance of the throttle valve, an auxiliary air passage connecting the main outlet from said main fuel nozzle and the low speed fuel outlet and an auxiliary fuel orifice delivering fuel into said auxiliary passage between the main outlet from said nozzle and the low speed fuel outlet.

2. In a carbureter, a main air passage, a 10 throttle valve, a main fuel nozzle delivering into said main air passage on the atmospheric side of said throttle, a constant level reservoir having a regulable outlet, a pas-

sage connecting said reservoir outlet and said fuel nozzle, a low speed fuel outlet 15 slightly in advance of the throttle valve, an auxiliary air passage connecting the main outlet from said main fuel nozzle and the low speed fuel outlet and an auxiliary fuel orifice delivering fuel from the main nozzle 20 into said auxiliary passage between the main outlet from said nozzle and the low speed fuel outlet.

In testimony whereof I affix my signature.

RAYMOND M. ANDERSON.
